(57) **CLAIM**

I claim the ornamental design for a carabiner with fire starter, as shown and described.

DESCRIPTION

FIG. 1 is a first perspective view of a carabiner with a fire starter showing my design;

FIG. 2 is a second perspective view thereof;

FIG. 3 is a front view thereof;

FIG. 4 is a first side view thereof;

FIG. 5 is a rear view thereof;

FIG. 6 is a second side view thereof;

FIG. 7 is a top view thereof; and,

FIG. 8 is a bottom view thereof.

The features shown in broken lines represent portions of the carabiner with fire starter which form no part of the claimed design.
